UNITED STATES PATENT OFFICE.

ROBERT H. WARREN, OF NEWARK, NEW JERSEY.

DESIGN FOR A STAIR-CARPET BUTTON.

SPECIFICATION forming part of Design No. 26,711, dated March 2, 1897.

Application filed January 23, 1897. Serial No. 620,475. Term of patent 7 years.

To all whom it may concern:

Be it known that I, ROBERT H. WARREN, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In the drawings, Figure 1 is a plan of my newly-designed stair-carpet button, and Fig. 2 is a section of the same on line *x*.

The leading feature of my design is a stair-carpet button having on the face thereof acorn

and leaf shaped ornamentals disposed 20 around the central perforation.

a indicates the stair-carpet button, and *b* the central perforation thereof.

c c are the acorn-shaped ornaments, the stems of which appear to radiate from the center of the button, and *d d* are the oak-leaf-shaped ornaments, alternating with the acorn-shaped ornaments.

What I claim as new is—

The design for a stair-carpet button herein 30 shown and described.

In testimony that I claim the foregoing I have hereunto set my hand this 24th day of September, 1896.

R. H. WARREN.
